UNITED STATES PATENT OFFICE.

GEORGE L. PRICHARD AND HERBERT HENDERSON, OF PORT ARTHUR, TEXAS, AS-SIGNORS TO GULF REFINING COMPANY, OF PITTSBURGH, PENNSYLVANIA, A CORPORATION OF TEXAS.

PROCESS OF PRODUCING LOW-BOILING OILS.

Application filed November 19, 1921. Serial No. 516,374.

To all whom it may concern:

Be it known that we, GEORGE L. PRICHARD and HERBERT HENDERSON, citizens of the United States, and residents of Port Arthur, in the county of Jefferson and State of Texas, have invented certain new and useful Improvements in Processes of Producing Low-Boiling Oils, of which the following is a specification.

10 This invention relates to processes of producing low boiling oils; and it comprises a method of converting higher boiling petroleum hydrocarbons (such as gas oil or kerosene) into lower boiling hydrocarbons, 15 (such as gasoline), wherein a boiling bath of a catalytic agent such as anhydrous aluminum chlorid or other metallic halid and higher boiling oil is established and maintained under standardized conditions of 20 temperature and concentration, said bath being replenished with oil and chlorid to make up for vapors of oil withdrawn and exhausted chlorid removed, the heat necessary for conversion and distillation being 25 supplied to the bath in such manner as to avoid injury to the aluminum chlorid; all as more fully hereinafter set forth and as claimed.

As is now known, high boiling petroleum 30 oils can be converted into lower boiling oils, such as gasoline, by the action of anhydrous aluminum chlorid. Unlike oils produced by destructive distillation or cracking, these oils are of saturated and "sweet" nature. 35 In so doing, the petroleum oil is boiled with a small proportion of chlorid, usually about five per cent, and the low boiling oils distilled away as fast as produced, using certain precautions in distillation to prevent 40 aluminum chlorid passing forward with the distillate.

The reaction mixture enters into active ebullition at a temperature which may be, and often is, materially below the boiling 45 point of the oil under treatment; and is ordinarily somewhere between 500° and 600° F. The aluminum chlorid does not dissolve in the body of oil to any great extent but melts down with a portion of it 50 to form a heavy viscid liquid underlying the rest of the oil; and to secure active conversion, energetic stirring is required to maintain a large area of contact between the two liquids. As the action goes on,

the lower layer thickens and stiffens progressively and finally becomes of a coky or asphaltic consistency. These changes are reflected in the work of the stirring mechanism which at first moves readily, then begins to require much power and finally moves more easily again. With these changes comes also a progressive diminution in converting or catalyzing power; the aluminum chlorid becomes exhausted and in order to keep up the flow of distillate, it is necessary to raise the temperature. In practice it is found, however, that the rapidity of this diminution in activity depends to a considerable extent on the conditions of operation; that the number of gallons of oil which can be treated by a given charge of chlorid is much affected by apparently small changes in heating and stirring conditions.

It is the object of the present invention 75 to rearrange and standardize conditions so as to secure an even and uniform production of vapors of low boiling oils in continuous operation, irrespective of the age of the charge of chlorid in use, and to utilize the activity of the chlorid to the fullest extent. To this end, a boiling bath of chlorid and oil of standardized composition is established and maintained in a suitable reaction chamber, replenishing the oil 80 by fresh supplies as oil disappears in the formation of removed vapors and supplying fresh active chlorid in proportion to the removal of the exhausted material. So far as is practicable, the heat required in 85 the operation is supplied elsewhere.

Looked at in one way, the stated process is really one of distillation; the high boiling oil is brought to a certain temperature and then distilled away as vapors of low 90 boiling oils. While the temperature required is not high, there must be an ample supply of heat. The amount of heat necessary is further increased by the practice of condensing and backtrapping a portion of 95 the vapors to prevent aluminum chlorid going forward to the condenser. In the usual practice, using stills heated at the base, much or most of this relatively large amount of heat must be supplied through a layer 100 of aluminum chlorid on the bottom of the still.

As already stated, the aluminum chlorid

melts down to a heavy viscid layer underlying the oil body and progressively becoming thicker in consistency. Whatever the efficiency of the stirrer, the bottom of the still cannot be kept free of aluminum chloride and particularly in the later stages of operation. The aluminum chlorid composition bakes on. And such aluminum chlorid composition as is present on the bottom of the still or bakes thereon is overheated; it is heated to a temperature above that prevailing in the reaction zone proper. This superheating of the aluminum chlorid composition rapidly destroys its activity.

For the stated reasons, in maintaining a standardized boiling bath in the reaction chamber, it is highly desirable that, so far as possible, all the heat be added elsewhere; that is, outside the chamber. In part the heat units necessary in the operation can be supplied as heat of incoming oil; as superheat of the oil. With some oils, considerable vaporization is practicable in the preheating and these vapors afford much heat to the bath in condensing therein. As a rule we do not desire in preheating and superheating to have such conditions of time and temperature as to cause much cracking. The reaction vessel itself may be heated to some extent; but it is advantageous to furnish as much of the heat as possible elsewhere. In furnishing the heat necessary, over and above that which is supplied as preheat, in the present invention there may be used a heating system employing superheated steam as a heating fluid. In so doing, the necessary heat units can be supplied without the use of temperature dangerous to the aluminum chlorid.

In the best embodiment of the present invention we use, a heat-insulated reaction vessel provided with means for supplying oil thereto, means for removing vapors therefrom, suitable backtrapping means to prevent aluminum chlorid going forward, and with means for supplying fresh chlorid and removing exhausted sludge. The incoming oil advantageously delivered below the normal oil level in the reaction vessel, is heated, prior to its entry into the reaction vessel, to as high a temperature as is practicable. For reasons stated, the formation of vapors in the preheating is not objectionable and is indeed desirable, in so far as it can be done without too much cracking. The reaction or converting chamber is further provided advantageously with interior heating means, such as a steam coil or the like.

In the described method of operation, the aluminum chlorid composition is not exposed to intense direct heat and its period of activity is made much longer; that is, a given amount of aluminum chlorid will suffice for the treatment of much more oil.

The aluminum chlorid is at no time exposed to a greater heat than that of the body of oil in which it occurs. And there is no formation of coked bodies or masses. When the activity of the aluminum chlorid is substantially spent, it occurs in a readily settling sludgy mass which gravitates to the bottom of the reaction vessel and since the fresh aluminum chlorid added continuously, or from time to time, stirs up with comparative readiness, this fact enables continuous operation. The settled material can be removed without substantially stopping the operation and the addition of fresh aluminum chlorid does not interfere with this removal.

In the accompanying drawings, showing one form of suitable apparatus for the performance of our process;

Fig. 1 is an elevation, partly in section, showing the preheater, converter and still, and condensers;

Fig. 2 is a top plan view of Fig. 1;

Fig. 3 is a vertical section on an enlarged scale through the converter and still, the air condenser being shown in elevation;

Fig. 4 is a section along line 4-4 of Fig. 3.

Referring to the drawings, 1 is a suitable foundation upon which is mounted the superstructure of the preheater. This consists of the walls 2 suitably lined with heat insulation 3 and fire bricks 4. The fire box 5 is provided with the oil and steam or other burner 6 and the bridge wall 7 for directing the gases into the furnace shaft. Mounted upon the walls 2 are the upright beams 8 of angle iron or the like connected by the cross heads 9, the structure being suitably braced by the angle irons 10. The preheater is suspended from this superstructure by means of the suspension rods 11 attached to the ears 12 of the upper drum 13. This drum is provided with the angle irons 14 which, in turn, rest on the angle irons 15 suitably secured by rivets or the like to supports 8. The lower drum 16 is in communication with the upper drum through a plurality of tubes 19. In the furnace shaft is provided a plurality of baffles 20 of fire brick or the like and near the top of such shaft is the flue 21 leading to the stack 22. The bottom of the furnace shaft may be provided with the depression 23 and the pipe line 24 for carrying off residual oil and the like to the receptacle 25. This inlet is to be used when the preheater is down for repairs or cleaning purposes and particularly when the tubes are being cleaned.

High boiling oil is admitted to the lower drum 16 through the oil inlet 26 which may be provided with a thermometer 27 in order to record the temperature of the incoming oil, whereby the efficiency of the heating unit

may be determined. The high boiling oil heated in the tubes 19 goes to the drum 13, from which it is delivered by means of the pipe 28 to the converting apparatus. This pipe 28 is insulated with asbestos or the like 29 and may be provided with a thermostat control, shown diagrammatically at 30, which may govern the amount of fuel oil or gas fed to the burner 6. When the temperature of the oil leaving the preheater is too high, this thermostat control will automatically close the valve on the oil or gas line and when the temperature of the oil leaving the heater is too low, it will open this valve. This is a standard equipment and the details are not shown.

The converter and still 31 is mounted upon supports 32 and is provided with the inlet 33 which may be a continuation of the pipe 28. To the inlet 33 is connected the pipe 34 which delivers hot oil to the cross pipe 35 which, in turn, has the branch pipes 36, all perforated as at 37 to permit even and uniform distribution of the preheated oil at a point near the bottom of the converter and still. The inlet 33 is located at a point near the bottom of the converter and still. The converter and still is provided with a plurality of petcocks 38, suitably valved (valves not shown), for determining the level of the contents of the apparatus. The converter may be made of steel or other material 39, suitably heat-insulated with asbestos, sil-o-cel or the like, 40, and it is provided advantageously near the top with the inlet 41, for delivering a magma of aluminum chlorid and oil. This magma is preferably delivered below the level of the aluminum chlorid and oil in the converter, as is shown by the down pipe 42. Mounted on the converter or still are the brackets 43 carrying the journal 44 through which passes the shaft 45 carrying the beveled gear 46, meshing with pinion 47 carried by sprocket wheel 48, driven by chain 49, leading to reduction gearing 50 suitably driven by belt or chain 51 from motor 52. The stirrer shaft 45 carries a plurality of stirrers 53 very much like propeller blades adapted to thoroughly stir or churn the contents of the still. These may be mounted on collars 54 suitably keyed to the shaft and some of the stirrers may be longer than the others to insure uniform and thorough mixing. The stirrer arms 53 carry sets of chains 55 to assist in the stirring and to scrub the walls. The shaft at the bottom is suitably journaled as at 56, such journal being supported by the brackets 57. The still may be heated by steam entering the coil 58 through inlet 59 and withdrawn through 60. The cone-shaped bottom or settling basin 61 of the still and converter is provided with the draw-off line 62 for the contents of the still or for drawing off the residual oil and aluminum chlorid or

"coky sludge", as it is termed. The coky sludge is sent to suitable recovery apparatus for recovering the hydrocarbons and the aluminum chlorid.

Vapors generated in the still and converter pass by vapor line 63 to a preliminary air cooled condenser 64 and uncondensed vapors pass therefrom by line 65 to a second air cooled condenser 66. Both of these condensers are provided with the backtrap lines 67 leading to the line 68 carrying condensates back to the still and converter, advantageously under the level of the contents thereof. From the second air cooled condenser 66, the vapors pass by line 69 to a final or water cooled condenser 70. Each of the air cooled condensers is provided with a thermometer 71 in order that the temperature of the vapors may be observed and the process regulated accordingly, as will be hereinafter described. The final or water cooled condenser 70 is mounted by means of supports 71' upon the foundation 72 and is provided with the drawoff 73 leading to the trapped connection 74. This trapped connection forms a seal so that any gases may pass through the line 75, while the liquid low boiling oil condensed may pass to the storage stock tanks through line 76.

The steam for coils 58 in the converter and still may be superheated in the superheater 77.

In a specific embodiment of our invention, gas oil or other higher boiling hydrocarbon oil is pumped to the preheater through the valved inlet 26 and is heated to a high temperature. In the case of gas oil, for example, the temperature may go anywhere from 500° to 700° F., while in the case of kerosene, the temperature may be somewhat less, say, 450° to 600° F., or more. Stack gases find exit through the flue 21 and thence to stack 22.

The higher boiling oil preheated in the preheater is delivered by means of the heat-insulated pipe 28 to the bottom of the still and converter 31, which may now be supplied or which may previously have been supplied with a charge of aluminum chlorid and oil from mixing apparatus (not shown). The stirring mechanism of the converter and still is set in motion and steam under pressure and at high temperature is admitted to the heating coil 58, so that the mixture of higher boiling oil and aluminum chlorid in the still or converter is kept at boiling temperature. The vapors of produced lower boiling oil (gasoline) together with vapors of higher boiling oil, aluminum chlorid and combinations of aluminum chlorid with the oil, pass to the preliminary cooler 64, where the majority of the high boiling oil, together with aluminum chlorid and its combinations with the oil, are condensed and are conducted back to the still or converter by the

line 68. The lighter vapors flow on to the second condenser 66, where condensates are returned by means of the line 67 and back-trap line 68 to the still. Vapors leaving condenser 66 go to the final water cooled condenser 70.

In operation, the still and converter should be run at such a rate that at no time the volume of the vapors in the second air 10 cooled condenser 66 or in the pipe leading therefrom shall be such as to maintain the thermometer 71 at a temperature higher than about 350° F., since at about that temperature and much above, the aluminum 15 chlorid and its combinations with the oil are in vapor form and would leave the system with the vapors of the lower boiling oils produced.

Cracking is not particularly harmful, 20 since the vapors and the oil from the preheater will both go to the converter and be converted into saturated products. The time factor enters into cracking and since the high boiling oil is constantly moving in the 25 preheater not much cracking takes place, even at relatively high temperatures. It is therefore possible to use relatively high temperature in the preheater. The higher 30 the temperature in the preheater or the greater the amount of vapors delivered to the converter, the less the amount is necessary in the converter itself.

The mixture in the converter and still is heated to the boiling temperature, which of 35 course depends upon the character of the higher boiling oil undergoing treatment and the percentage of aluminum chlorid in the converter. With gas oil boiling around 40 600° F. and with 5 per cent of aluminum chlorid in the converter, to cause boiling it is necessary to heat the mixture to a temperature of from 500° to 550° F.

The stirring mechanism in the converter should be operated at a speed sufficiently 45 high to thoroughly mix the aluminum chlorid and the oil in the converter.

While the process may be run as a "batch" 50 process, we prefer to operate continuously, supplying in proper ratio the aluminum chlorid in admixture with enough oil to make it fluid through inlet 41 and the higher boiling oil from the preheater through inlet 33.

After a time, the aluminum chlorid and 55 its combinations with the oil form a heavy residue containing more or less coke which settles in the conical-shaped bottom 61 of the converter and such residue may be withdrawn by means of the outlet 62 and sent to 60 suitable recovery apparatus. This residue, which is termed "sludge", contains very little free oil, since the sludge settles in the coned bottom of the converter.

We are aware that it has been proposed 65 to heat the high boiling oil for the purpose

of drying it before adding to the still containing the aluminum chlorid, but it is our purpose to do more than this and superheat the incoming oil to a relatively high temperature and in effect use it for supplying substantial quantities of heat units to the converter and still. 70

While aluminum chlorid in anhydrous form is the best catalytic agent for the purpose now known to us, other catalytic agents 75 may be used, such for instance as other metallic halids—ferric chlorid and zinc chlorid; but they are not so active as aluminum chlorid.

While the preheated oil supplied to the 80 converter is advantageously of the same general character as that already contained therein, it is not necessarily so; as it is frequently convenient to change the supply of oil from one grade to another in continuous 85 operation; and furthermore, in any event, the oil of the bath is always composed in part of refluxed oils coming from the back-trapping means, and therefore may differ somewhat from admitted oil. 90

We claim:

1. The process of converting higher boiling oils into lower boiling oils which comprises establishing and maintaining a boiling body of higher boiling oil and aluminum chlorid, conducting vapors of lower boiling oils formed away from such body, and supplying additional high boiling oil substantially in liquid form to said body at a temperature higher than the boiling point 100 of the body.

2. The process of converting higher boiling oils into lower boiling oils which comprises establishing and maintaining a boiling body of higher boiling oil and aluminum chlorid, conducting away from such body vapors of lower boiling oils formed, supplying additional higher boiling oil substantially in liquid form at a temperature higher than said body and supplying heat 110 directly to said body of higher boiling oil and aluminum chlorid. 105

3. The process of converting higher boiling oils into lower boiling oils which comprises establishing and maintaining a boiling body of higher boiling oil and aluminum chlorid, conducting away from such body vapors of lower boiling oils formed, supplying additional higher boiling oil substantially in liquid form at a temperature higher than said body and supplying heat directly to said body of higher boiling oil and aluminum chlorid, said heat being supplied at a temperature not much above that of said body. 115 120

4. The process of converting higher boiling oils into lower boiling oils which comprises establishing and maintaining a boiling body of higher boiling oil and aluminum chlorid, conducting away from such 125 130

- body vapors of lower boiling oils formed, and supplying additional high boiling oil substantially in liquid form to said body at a temperature above 600° Fahrenheit.
5. The process of converting higher boiling oils into lower boiling oils which comprises establishing and maintaining a boiling body of higher boiling oil and aluminum chlorid, conducting vapors of lower boiling 10 oils formed away from such body, supplying additional higher boiling oil substantially in liquid form at a temperature above 600° F. and supplying heat directly to said body of higher boiling oil and aluminum chlorid.
15. 6. The process of converting higher boiling oils into lower boiling oils which comprises establishing and maintaining a boiling body of higher boiling oil and aluminum chlorid, conducting vapors of lower boiling 20 oils away from such body, supplying additional higher boiling oil substantially in liquid form at a temperature above 600° F. and supplying heat directly to said body of higher boiling oil and aluminum chlorid, 25 said heat being supplied at a temperature not much above that of said body.
7. The process of converting higher boiling oils into lower boiling oils which comprises heating a mixture of higher boiling 30 oil and aluminum chlorid to from 500 to 600° F., conducting away vapors of lower boiling oils formed, and supplying additional higher boiling oils substantially in liquid form at a temperature above 600° F.
35. 8. The process of converting higher boiling oils into lower boiling oils which comprises heating a mixture of higher boiling oil and aluminum chlorid to from 500 to 600° F., conducting away vapors of lower boiling 40 oils formed, supplying higher boiling oil substantially in liquid form at a temperature above 600° F., and supplying additional heat directly to the body of higher boiling oil and aluminum chlorid.
45. 9. The process of converting higher boiling oils into lower boiling oils which comprises heating a mixture of higher boiling oil and aluminum chlorid to from 500 to 600° F., conducting away vapors of lower boiling 50 oils formed, supplying higher boiling oil substantially in liquid form at a temperature above 600° F., and supplying additional heat directly to the body of higher boiling oil and aluminum chlorid, said heat being 55 supplied at a temperature not much above that of said body.
10. In the conversion of higher boiling oils into lower boiling oils with the aid of aluminum chlorid, the process which comprises establishing and maintaining a boiling 60 body of higher boiling oil and aluminum chlorid, conducting away vapors of lower boiling oil formed, heating higher boiling
- oil to a temperature higher than the temperature of said body, and adding the so heated 65 oil substantially in liquid form to said body of oil and aluminum chlorid.
11. In the conversion of higher boiling oils into lower boiling oils with the aid of aluminum chlorid, the process which comprises 70 establishing and maintaining a boiling bath of oil and aluminum chlorid and supplying superheated oil thereto substantially in liquid form.
12. In the conversion of high boiling oil 75 into low boiling oils with the aid of aluminum chlorid, the process which comprises establishing a boiling bath of higher boiling oil and aluminum chlorid and supplying superheated higher boiling oil of the same 80 character thereto substantially in liquid form.
13. In the conversion of higher boiling oils into lower boiling oils with the aid of 85 aluminum chlorid, the process which comprises establishing a boiling bath of oil and aluminum chlorid, removing vapors of lower boiling oil produced and supplying superheated oil thereto substantially in liquid 90 form in proportion to removal of vapors.
14. The process of producing lower boiling 95 oils from higher boiling oils which comprises establishing and maintaining a boiling body of higher boiling oil and aluminum chlorid, heating higher boiling oil to a temperature higher than the temperature of the boiling body, conducting away from said boiling body vapors of lower boiling oil formed, adding to said boiling body the so heated higher boiling oils substantially in liquid form at a temperature higher than the temperature of said boiling body, removing contaminated and used aluminum chlorid residue from the body of higher boiling oil and supplying fresh aluminum chlorid 100 to said body of higher boiling oil.
15. The process of converting higher boiling 105 oils into lower boiling oils which comprises heating a mixture of aluminum chlorid and higher boiling oil to a temperature sufficient to cause ebullition, agitating the mixture, allowing sludge of aluminum chlorid formed to settle under the body of higher boiling oil and aluminum chlorid, removing such sludge, adding additional aluminum chlorid to said mixture of aluminum chlorid and the higher boiling oil, conducting away 110 vapors of lower boiling oil formed, and adding to the said mixture higher boiling oil heated to a temperature above that of the 115 body of oil and chlorid.

In testimony whereof we have hereunto signed our names at Port Arthur, Texas, this 14th day of November, 1921.

GEORGE L. PRICHARD.
HERBERT HENDERSON.
